(57) **CLAIM**

The ornamental design for a chord for trusses, as shown and described.

DESCRIPTION

FIG. 1 is a top, front perspective view of the chord for trusses.

FIG. 2 is a top view thereof.

FIG. 3 is a bottom view thereof.

FIG. 4 is a front view thereof, with the back view being the same.

FIG. 5 is a right-side view thereof; and,

FIG. 6 is a left-side view thereof.

The broken lines represent unclaimed subject matter and form no part of the claimed design.
